UNITED STATES PATENT OFFICE

PHILO J. HOLZHAUER, OF DETROIT, MICHIGAN, ASSIGNOR TO GENERAL MOTORS CORPORATION, OF DETROIT, MICHIGAN, A CORPORATION OF DELAWARE

RADIATOR SCREEN

Application filed April 13, 1929. Serial No. 354,879.

This invention relates to a screen which is adapted to be placed in front of the radiator of an automotive vehicle to improve the appearance of the front end of the vehicle, and resides, particularly, in the provision of means for detachably and, yet, securely fastening the screen to the shell of the radiator.

For a better understanding of the nature and the objects of the invention, reference is made to the following specification in which is described the preferred embodiment of the invention which is shown in the accompanying drawing.

In the drawing:

Figure 1 is a front elevation of the screen installed on the radiator of a vehicle.

Figure 2 is an enlarged fragmentary section taken on the line 2—2 of Figure 1.

Figure 3 is an enlarged fragmentary side elevation, with parts broken away and in section, taken as indicated by the line 3—3 of Figure 1.

Figure 4 is a section taken on the line 4—4 of Figure 3.

Figure 5 is a fragmentary section taken on the line 5—5 of Figure 2.

Figure 6 is an enlarged fragmentary section taken on the line 6—6 of Figure 1.

In the drawing, the reference character 10 indicates the shell of the radiator of an automotive vehicle, and the reference character 11 an opening in the upper depending flange of the shell through which the stud 35 which secures the usual medallion to the shell ordinarily projects.

The screen includes a frame or border 12 which has, in general, the same contour as the radiator shell. The frame or border is angle-shaped in cross-section and is preferably made of sheet metal by a stamping operation. Between the inner margins of the frame or border 12 and secured to the vertical flanges thereof, preferably by soldering, extends a sheet 13 of screen wire of the usual or any desired weave.

To support the screen from the radiator shell, there is provided a stud 14 which is, as shown in the drawing, adapted to 50 place the usual medallion carried by the

radiator shell. On the outer end of the stud, there is provided a button-like head 15 over which is adapted to hook a stamping 16 which is secured, preferably by welding, to the upper side of the frame or border 12 of the screen. To prevent movement of the lower end of the screen with respect to the radiator shell, there are provided fasteners 17 and 18', as shown on the drawing. Each of these fasteners consists of a device which is similar to an ordinary hood fastener and consists of a rod 18 which is connected at one end by a pivot 19 and a bracket 20 to the radiator shell and has on its opposite end a head 21 which is slidably mounted in a tube 22. The end of the tube 22 through which the rod 18 extends into the interior thereof is crimped over to form a bearing surface for one end of a coil spring 23 which bears at its opposite end against the head 21 on the rod 18. On the end of the tube 22 opposite that through which the rod 18 enters thereinto, there is secured a hook-like member 24 which is adapted to engage over a button-like element 25 which is secured to the frame or border 12 of the screen at a point substantially higher than the level of the pivot 19 so that the spring tends to pull the screen downwardly and maintain the stamping 16 securely hooked over the head of the stud 14.

To prevent the screen from rattling against the radiator shell during movement of the vehicle, there are provided blocks 26 of suitable resilient material, such as rubber, which are secured to the border or frame of the screen at spaced points and which are adapted to engage against the radiator shell and maintain the shell and the border 90 or frame spaced a short distance apart.

In the upper depending flange of the frame or border of the screen, there is provided an opening 27 through which the securing stud 28 of the usual radiator medallion 29 is adapted to extend so that the medallion may be displayed when the screen is in use.

Besides improving the appearance of the front end of the vehicle on which it is used, 100

it will be obvious that my screen will function to prevent particles of foreign matter from entering the radiator core and the space enclosed by the engine hood of the vehicle.

5 Although I have shown and described a preferred embodiment of my invention, it is to be understood that this has been done merely by way of example, and not by way 10 of limitation, and that the scope of my invention is to be determined only by the appended claims.

I claim:

15 1. The combination with a radiator shell of a member having the same general contour as the radiator shell adapted to be secured to the radiator shell in advance thereof, means to secure the member to the shell including a hook-like element through 20 which the member is adapted to be supported from the shell, and spring-tensioned means independent of the hook-like element adapted to maintain the hook-like element in engagement with the shell.

25 2. The combination with a radiator shell and a member having the same general contour as the shell adapted to be secured to the shell in advance thereof, an opening in the member through which the stud of the 30 usual radiator medallion is adapted to extend, and a stud adapted to replace the medallion in the radiator shell and through which the member is adapted to be supported from the shell.

35 3. The combination with a radiator shell and a member having the same general contour as the shell and which consists of a continuous frame or border and a foraminous member secured to the inner margins 40 of the frame or border and extending there-between, means to secure the member to the shell, and resilient means to space the member from the shell.

45 4. The combination with a radiator shell of a member having the same general contour as the radiator shell adapted to be secured to the radiator shell in advance thereof, inter-engaging means on the radiator shell and the member to support the 50 member from the shell, spring tensioned means independent of the inter-engaging means to maintain the inter-engaging means in engagement, and resilient means interposed between the member and the shell to space the member from the shell.

55 5. In combination with a radiator shell and a rigid member which is adapted to be secured to the shell in advance thereof, inter-engaging means adjacent the upper ends of the shell and the member through which the member is adapted to be supported from the shell, and resilient means extending between the lower portions of the shell and the member and arranged to exert a downward pull

on the member to maintain the inter-engaging means in engagement.

6. In combination with a radiator shell and a member which includes a rigid frame or border which is adapted to be secured to the shell in advance thereof, means to secure the member to the shell including a hook-like element through which the member is adapted to be supported from the upper end of the shell, and resilient means extending between the lower portions of the shell and the member and arranged to exert a downward pull on the member to maintain the hook-like element in engagement.

7. The combination with a radiator shell and a member adapted to be secured to the shell in advance thereof of an opening in the member through which the stud of the usual radiator medallion is adapted to extend, and a stud adapted to replace the medallion in the radiator shell and through which the member is adapted to be supported from the shell.

In testimony whereof I affix my signature.

PHILO J. HOLZHAUER.
